Application October 8, 1934, Serial No. 747,355

2 Claims.

(Cl. 2-93)

This invention relates more particularly to coats for men of the type illustrated in Letters Patent of the United States, No. 1,971,125, issued to me August 21, 1934. The object, generally, of the present invention is similar to that set forth in said patent, to wit; to provide an improved construction of coat in which the upper back portion is normally maintained in a smooth and unrumpled condition. The particular object in the present instance is to produce a coat of said type of simpler and more economical construction. Other objects will appear from the following description.

The invention is embodied in the example herein shown and described, the features of novelty being finally claimed.

In the accompanying drawings—

Figure 1 is an elevational view of the back of the coat according to the invention.

Fig. 2 is an elevation of the side of the coat.

Fig. 3 is a view illustrating how the piece is cut for the back.

Fig. 4 illustrates the seaming of the piece illustrated in Fig. 3.

Fig. 5 illustrates a mid-fracture of the back piece having applied thereto an arched-shaped flexible stiffening or padding at the inner side of the piece with a portion of said stiffening broken out.

Fig. 6 is a vertical section on line VI—VI Fig. 1.

Fig. 7 is a view like Fig. 1 of a modification.

Fig. 8 is a view of the side of Fig. 7.

Fig. 9 illustrates the back portion of Fig. 7 before stitching.

Fig. 10 illustrates a mid-fracture of the stitched back piece having applied thereto an arch-shaped flexible stiffening or padding at the inner side of the piece.

Fig. 11 illustrates a vertical section on, say line XI—XI Fig. 7.

Referring first to Figs. 1 to 6 inclusive the back is made of a single piece of fabric cut from the top in upright lines 12, 12 to points in the region where the back is to cover or lie on the rumps of the wearer, said lines terminating by shorter cut or incised lines 13, 13 inclined inward. In stitching the cut portions together the outer sections 14, 14, are drawn inward and seamed as illustrated in Fig. 4, such seaming including the cut lines 13, 13. The effect of this drawing inward and seaming of the inclined cut portions at 13, 13 is to cause a horizontal contraction of the fabric at the region between the upper back portion and the tail of the coat and thereby forming a bulge at the top of the tail portion so that the

back conforms to the shape of the body at said region. A consequence of thus shaping the back portion of the coat is that the rumps can, in ordinary or normal movements, operate within the bulged tail portion without disturbing the upper back portion.

In order the better to insure the effect desired there is secured by stitching to the inner side of the back an upwardly arched flexible padding strip 15 that lies across the seams of the short cuts 13, 13, as best shown in Fig. 5 and an arched belt, so called, 16 on the exterior of the back of the coat that preferably parallels and covers the stitching of the padding strip 15. The two members 15 and 16 cooperate in strengthening the back at the region of the top of the rumps and tend to prevent the imparting of motion of the tail portion to the upper back and conversely. The usual lining (not shown) of the coat covers and conceals the padding strip.

Instead of seams in the top of the back of the coat pleats can be substituted, the small cuts, as shown, being made at the bottom of the upper portion of the back to permit contraction and thereby produce the bulging effect above the rumps.

Referring now to Figs. 7 to 11 inclusive the two symmetrical pieces 17 and 17^a of Fig. 9 are intended to represent the fabric as cut to form the back, as shown in Figs. 7 and 8. The broken lines on said pieces 17 and 17^a represent seaming lines after the coat is made. The matching middle lines of said back pieces are shown as incised or cut with inward curves 18 and 18^a that when stitched together as by the broken lines narrows the back of the coat at that region and causes a bulge at the top of the tail portion of the coat.

In order to sustain the upper back of the coat in a smooth and unrumpled condition there is secured by stitching at the inner side of the back an upwardly arched flexible strip 19 that lies across the seam at the line of the bulge, substantially as shown in Figs. 10 and 11, and an arched belt, so called, 20 on the exterior of the back of the coat. Said belt preferably parallels and covers the stitching of the padding strip 19. The two members 19 and 20 cooperate in strengthening the back at the region of the top of the rumps and tend to prevent the imparting of motion to the tail portion to the upper back portion and conversely. The usual lining (not shown) of the coat covers and conceals the padding of the coat.

The upper back portion of the coat can be made whole or uncut or with pleats in which case the cut can extend upward to include the inward

curves 18 and 18^a so that when such portions are drawn together and stitched the bulge at the top of the rumps is formed. When pleats are made in the back in the form shown in Fig. 4 the inclined cut 13, 13 can be made in the piece to permit the drawing in of the goods.

The forms of the parts can be changed without departing from the gist of the invention as claimed.

10. What I claim is:

1. A coat including in its back a fabric piece vertically continuous from the collar portion to the lower end of the tail portion and having in its waist line generally vertical incisions in opposed and spaced relation to each other, said incised portions drawn and sewed together whereby

there is formed a bulge to rest over the rump of the wearer, and a flexible reinforcing member extending and secured to the back across said incised portions to maintain said bulge.

2. A coat including in its back a fabric piece vertically continuous from the collar portion to the lower end of the tail portion and having in its waist line generally vertical incisions in opposed and spaced relation to each other, said incised portions drawn and sewed together whereby there is formed a bulge to rest over the rump of the wearer, and an upwardly arched flexible reinforcing member extending and secured to the back across said incised portions to maintain said bulge.
